DESIGN FOR A CORNER CLAMP FOR STORE FRONT CONSTRUCTION

Application filed April 2, 1931. Serial No. 39,352. Term of patent 14 years.

To all whom it may concern:

Be it known that we, FRED HIMMEL and ISIDORE HIMMEL, citizens of the United States, residing at New Haven, in the county of New Haven and State of Connecticut, have invented a new, original, and ornamental Design for a Corner-Clamp for Store-Front Construction, of which the following is a specification, reference being had to the accompanying drawings, forming part thereof.

Fig. 1 is a front view of a corner-clamp for store-front construction showing our new design; and

Fig. 2 is a plan view of the same.

We claim:

The ornamental design for a corner-clamp for store-front construction as shown.

FRED HIMMEL.
ISIDORE HIMMEL.
